UNITED STATES PATENT OFFICE

ELTON D. KOHR, OF YORK, PENNSYLVANIA

DESIGN FOR A FROZEN-PRODUCT-MACHINE SUPPORTING STAND

Application filed January 7, 1931. Serial No. 38,232. Term of patent 14 years.

To all whom it may concern:

Be it known that I, ELTON D. KOHR, a citizen of the United States, residing at York, in the county of York and State of Pennsylvania, have invented a new, original, and ornamental Design for Frozen-Product-Machine Supporting Stand, of which the following is a specification, reference being had to the accompanying drawing, forming a part hereof.

Figures 1, 2, 3 and 4 are respectively a front elevation, a rear elevation, a side elevation and a top plan view, showing my new design.

I claim:

The ornamental design for a frozen-product-machine supporting stand, as shown.

ELTON D. KOHR.
